UNITED STATES PATENT OFFICE.

GEORGE L. HOFFMAN, OF HAMILTON, OHIO.

RIDING-PLOW.

No. 905,533.

Specification of Letters Patent.

Patented Dec. 1, 1908.

Application filed September 30, 1907. Serial No. 395,107.

To all whom it may concern:

Be it known that I, GEORGE L. HOFFMAN, a citizen of the United States, residing at Hamilton, Butler county, Ohio, have invented a new and useful Improvement in Riding-Plows, of which the following is a specification.

My invention relates to riding plows, and the objects of my improvement are to provide automatic means for lessening the lateral movement of the seat when the plow is thrown out of the ground by an obstruction; to provide automatic means for maintaining the land wheel in contact with the different vertical positions of the plow; to provide such construction and assemblage of parts as will lessen the draft, as will cause the plow to pass obstructions with greater facility and less danger of being broken, and as will prevent any extreme and sudden lateral movement of the seat whereby the operator might be thrown or injured. These objects are attained in the following described manner, as illustrated in the accompanying drawings, in which:—

Figure 1 is a plan of a riding plow embodying my improvements; Fig. 2, a side elevation; Fig. 3 a rear elevation; Fig. 4 a detail of construction showing parts in vertical section on the line of the land wheel axle and Fig. 5, a section on the line *a—a* of Fig. 1.

In the drawings, 1 represents the housing formed with a slot 2, 3 a short pole or hitch which is pivotally secured thereto. The front axle 4 is formed with a vertical bearing 5 and with a vertical bracket 6 which terminates in a segmental rack 7. Said axle is longitudinally adjustable in the housing by means of a bolt in slot 2. The front spindle 8 whereon the front furrow wheel 9 is journaled is turned at an obtuse angle and swiveled in bearing 5. A detent lever 11 fulcrumed on bracket 6 cooperates with rack 7 and is connected with spindle 8 by means of a link 12 for moving and maintaining the spindle with the wheel 9 in different vertical positions in relation to the axle 4. A bar 13 projects in a forward direction from spindle 8 and a brace 14 is adjustably connected thereto and to the hitch 3 for automatically moving and maintaining the spindle with the wheel 9 in a direction substantially parallel with that of the hitch.

55 A front beam 15 formed with an obtuse

angle is secured to the housing, and a rear beam 16 formed with a similar angle is secured thereto by means of a bracket 17. Said bracket is formed of two members pivotally connected together by means of a bolt or pintle 18 whereby they may be adjusted with the beams in different horizontal angles in relation to each other and maintained in adjusted position by means of a pin or clamping bolt 19 being inserted through holes formed through the members of the bracket.

Concavo-convex disks 21 are rotatively secured to the respective beams by means of brackets and spindles 22 and 23 in the usual manner. A sleeve 24 provided with a segmental rack 25 is secured on the rear beam 16 and a crank spindle 26 provided with the land wheel 27 is journaled therein. A detent lever 28 secured on said spindle cooperates with said rack and serves to rotatively move and maintain said spindle with wheel 27 in different vertical positions. A rear extension 29 of beam 16 connected thereto by means of a hinge joint 30 is formed with a horizontal arm 31, with a vertical bearing 32 and with a stop 33. A rear spindle 34 provided with the rear caster or furrow wheel 35 is turned at an angle and swiveled in said bearing 32 wherein its movement with the wheel 35 in a forward direction is limited by contact with the stop 33. The seat bar 36 provided with the operators seat 37 and with the foot rest 38 is secured to and supported by the arm 31 of the hinged member 29.

A coiled spring 41 is pivotally secured at one end in arm 31 and adjustably secured at the other end in an arm or lug 42 which projects laterally from the rear beam 16 at a point near the angle therein. Said spring serves to maintain the hinged member 29 under a yielding pressure in its normal closed position and in the line of beam 16.

A coiled spring 43 adjustably secured at one end to the foot rest 38 and secured at the other end to the detent lever 28 reinforces the action of spring 41 in maintaining member 29 in the closed position and serves also to yieldingly actuate the lever 28 in a rearward direction for maintaining the land wheel 27 in continuous contact with the ground. A link or clevis 44 swiveled on the end of the detent lever 28 serves to lock the detent 45 thereon out of engagement with

the segmental rack 25 when desired, as shown in Fig. 4.

In operation, when the detent 45 is held out of engagement with the rack 25 the exertion of the spring 43 on lever 28 permits the disks to ride over an obstruction or through hard places in the soil without lifting the land wheel, thereby making the draft more constant and much easier on the team. When either of the disks strikes a permanent obstruction, as a concealed rock, they are lifted and quickly thrown laterally in the direction of the land wheel. Where the seat is rigidly secured to the beam, this sudden movement throws the seat laterally so far that the operator is thrown to the ground with danger of injury and of the escape of the team. The hinge joint in the beam obviates this danger by being automatically opened under any sudden movement of the disks with the beams toward the land wheel, while the seat is permitted to remain in substantially the same position. After the obstruction is passed the spring 41 serves to automatically and quickly close the joint in the beam and return the disks to their proper operative positions instead of permitting them to continue running too far inland. When released by the link 44 on lever 28 the detent may be engaged with the rack 25 to lock the land wheel with the disks in the raised position for carrying them from place to place when not in action. It may also be used when desired to lock the land wheel with the disks at a predetermined cutting depth if desired.

My improvement may be applied with equal advantage to a riding plow having either one or a plural number of disks, or to a plow wherein the ordinary shares and mold boards are used instead of disks.

Having fully described my improvement what I claim as my invention and desire to secure by Letters Patent of the United

States is:—

1. A riding plow comprising a beam, a seat movable laterally in relation thereto, a crank axle journaled on the beam and provided with a ground wheel, and a spring arranged to yieldingly maintain both the seat and the axle with the ground wheel in predetermined positions.

2. In a riding plow, the combination of a beam consisting of two members, a hinge joint connecting them together, a spring arranged to move and yieldingly maintain the

joint in the closed position, and a seat and a disk supported on the respective members.

3. A riding plow comprising a beam, a seat movable laterally in relation thereto, a crank axle journaled on the beam and provided with a lever, and a spring arranged to move and yieldingly maintain the lever with the axle in predetermined rotative positions, said spring being also arranged to yieldingly maintain the seat in a predetermined position in relation to the beam.

4. In a riding plow, the combination of a beam provided with a lateral break joint, a crank axle journaled thereon and provided with a land wheel, a lever secured to the axle, and a spring attached to the lever and arranged to rotatively move the axle and also to close the joint.

5. In a riding plow, the combination of a beam provided with a lateral break joint, means for automatically closing the joint, a seat carried by the beam and rearwardly of the joint, a crank axle journaled on the beam in front of the joint and provided with a land wheel, and a spring arranged to return the axle and to simultaneously reinforce the action of said means in closing the joint.

6. In a riding plow, a caster wheel, a beam having one of its ends supported thereby and provided with a seat and with a lateral break joint, automatic means for yieldingly maintaining the joint closed and a furrow opener secured to the beam on the opposite side of the joint from the wheel.

7. A riding plow comprising a beam, a member hinged thereon and provided with a seat, a crank axle journaled on the beam and provided with a ground wheel, and a spring arranged to simultaneously turn the axle and move the hinged member with the seat laterally in relation to the beam.

8. In a riding plow, the combination of a beam consisting of two members, a joint connecting said members together, a crank axle journaled on one of said members and provided with a ground wheel, a seat supported on said other member, and spring actuated mechanism arranged to yieldingly resist the lateral movement of the member with the seat, and to simultaneously resist the turning of the axle for raising the wheel.

GEORGE L. HOFFMAN.
